WELL PACKER

Cicero C. Brown, Houston, Tex.

Application December 18, 1936, Serial No. 116,447

11 Claims. (Cl. 166—10)

This invention relates in general to a packer apparatus for oil wells, and more particularly has reference to the packer apparatus which is to be employed adjacent the bottom of the oil well to 5 form seals between the various parts of the equipment at the bottom of the hole.

In the past it has been customary to run into a well hole a casing for lowering this casing to some predetermined point, such as for example a 10 position adjacent the top of the producing formation. After the casing has been lowered into position, the lower end is cemented in place so as to provide a seal between the casing and the wall of the hole, and the drilling is then completed below the lower end of the casing into the 15 producing formation. At this point there is provided a screen and liner, the screen consisting of lengths of pipe of a diameter sufficiently small to pass downwardly through the casing, the pipe 20 being of some suitable construction having openings therethrough so as to permit the passage of fluid from the well hole and yet serve as a support for the formation and as a screen to prevent the ingress of sand and other debris. 25 The liner, which is at the upper end of this screen, and which is ordinarily lowered into the well with the screen, is provided at a position which will lie within the lower end of the casing with a packer element adapted to seal off the space between the liner and the casing. By this means it 30 will readily be seen that fluid will be forced to enter the casing only through the screen and through the interior of the liner, and will be prevented from entering the casing through the 35 space between the liner and the casing.

It is also customary to employ a string of tubing extending from the upper end of the well downwardly and preferably into the interior of the screen itself. This is for the purpose of better 40 providing for the flowing of the well both in bringing it into production and in carrying out such later operations as may become desirable. This string of tubing may if desired be employed for lowering the screen and liner into position 45 and after the screen and liner have been positioned in the lower end of the well to cause the expansion of the packer between the liner and the lower end of the casing.

It is an object of this invention to provide a 50 packer assembly which is not only capable of forming a seal between the liner and the lower end of the casing, but which is also capable of forming a seal between the interior of the liner and the lower end of the tubing so that fluid entering the screen will be forced to travel to the

surface of the well through the tubing, and will not be permitted to enter the casing.

It is a further object of this invention to provide a packer structure of the type set forth in which the formation of the seal between the liner and the casing and the formation of the seal between the liner and the tubing will take place substantially simultaneously.

Another object is to provide a construction of the type set forth in which the seal between the liner and the tubing may be readily removed without construction after the same has been set in position.

Another object is to provide a device for expanding the packings between the liner and the casing, and between the liner and the tubing which will be low in cost and sure in its operation.

Another object of this invention is to provide a packing structure which may be readily removed from the well after it has been set in place therein and expanded.

Other objects and advantages will become apparent from the following description taken in connection with the accompanying drawings wherein there is set forth one embodiment of this invention. It is to be distinctly understood, however, that this embodiment is set forth by way of illustration and not by way of limitation, and that this invention is to be limited in its scope only by the prior art, and by the terms of the appended claims.

In the drawings:

Fig. 1 is a vertical cross section of the lower end of a well hole illustrating in elevation a portion of the equipment therein, parts of the equipment being broken away and shown in section for purposes of illustration.

Fig. 2 is a view similar to Fig. 1 but showing a continuation of the upper portion of Fig. 1 and illustrating the packer construction in accordance with this invention after the packings have been expanded to form the respective seals.

Fig. 3 is a view partly in section illustrating more in detail the equipment shown in Fig. 1, the same being in the position it occupies prior to the setting of the packers.

Fig. 4 is an elevation partly in section illustrating the equipment shown in Fig. 2 before the packers have been expanded to form the respective seals.

Fig. 5 is a view on a reduced scale showing a vertical cross section of a well hole having the equipment constructed in accordance with this

invention in place therein prior to the expansion of the respective packings.

Fig. 6 is a view similar to the lower portion of Fig. 3 illustrating one of the steps in the operation of setting the equipment in place in a well or in removing the same therefrom.

Fig. 7 is a view similar to Fig. 4 illustrating the manner in which the seal between the liner and the tubing may be removed after the packing 10 forming the said seal has been expanded.

Fig. 8 is a vertical cross section of the valve mechanism employed at the lower end of the screen and illustrated in Figs. 1, 3 and 6.

Fig. 9 is a top plan view of said valve structure. 15 Fig. 10 is a view illustrating in detail one of the elements employed in removing the seal between the liner and the tubing after the packing forming the same has been expanded.

Referring again to Fig. 1, the numeral 1 designates the lower end of the casing which is ordinarily lowered into a well, and the numeral 2 that portion of the well hole which is drilled below the lower end of the casing and into the producing formation 3. It is to be noted that the 25 portion 2 of this hole will be of whatever length may be desired in view of the nature of the formation encountered. In some instances this is very short, and in others it may be several hundred feet in length.

30 Inside of the casing 1 there is lowered a tubing 4 which in this instance connects at the lower end thereof to the shoe 5. The shoe 5 has blades 6 extending downwardly from its lower end and openings 7 therein through which fluid 35 may be forced during the lowering of the device into the well, and thereafter in washing the well.

By reference to Fig. 3 it will be seen that this shoe has a transverse guide and support 8 therein, and that it is exteriorly threaded at 10 to receive 40 the fitting 11. This fitting 11 is provided with an inwardly extending flange 12 forming a downwardly facing shoulder, and a valve seat member 13 is held in place between this shoulder 12 and the upper end of the shoe 5. A valve 14 is mounted 45 below the valve seat member 13 and adapted to seat against the opening therethrough, being yieldingly urged against its seat by means of a spring 15 which bears against the guide and support 8. The valve 14 is also provided with a downwardly extending valve stem 16 which slides through an opening in the guide and support 8, and is guided thereby.

At its upper end the fitting 11 is provided with 55 internal threads 17 extending for a considerable portion of its length and terminating in an inwardly extending flange 18. A cup 19 forming one portion of a valve combination, as will hereinafter appear, is provided with an exteriorly threaded outwardly extending flange 20 in engagement with the threads 17 and its lower end extends downwardly past the flange 18. A second cup 21 forming the other portion of the valve assembly is provided with a downwardly extending axial pin 22 which projects through an opening in the cup member 19 and is secured in place by means of a nut 23 below the cup member 19. It will be noted that the inner wall of the cup member 19 and the outer wall of the cup member 21 are slightly tapered so as to form a taper fit 70 between these two members when they are interengaged as illustrated. The cup member 19 is formed with a lateral opening 24 illustrated in Fig. 8, and the cup member 21 with a lateral opening 25 adapted when the cup members are

properly positioned with respect to each other to register and form a fluid passageway.

The cup member 21 is provided with an outwardly extending flange at its upper end and with a lug 26 thereon adapted to cooperate with a lug 27 formed on the upper end of the cup member 19 to limit relative movement of these cup members with respect to each other. These lugs 26 and 27 are preferably so positioned that they will come in contact when the openings 24 10 and 25 are in position at right angles to each other. In other words, the movement of the valve elements with respect to each other will be stopped when the valve is in fully closed position. For the purpose of rotating the valve element 21 with respect to the element 19, the element 21 is provided on its inner surface with longitudinally extending lugs 28 having tapered upper ends 30.

Threaded into the threaded section 17 of the member 11 above the flanges of the cup members 19 and 21 just referred to is a member 31 having a sleeve-like portion 32 extending upwardly therefrom and off-set inwardly intermediate its upper and lower ends to provide a downwardly facing inclined shoulder 33. A stop member 34 is inserted in an opening provided therefor in the element 31 and the fitting 11 and serves to lock the element 31 in place within the fitting 11, and also to provide a stop member for 30 use in connecting and disconnecting the tubing from the set shoe in a manner presently to be described.

Secured to the lower end of the tubing 4 is a special coupling member 35 having a thickened 35 lower portion internally threaded to receive the upper end of a fitting 36. The lower end of the coupling member 35 is formed with a race for an anti-friction bearing, the other race of which is formed on the upper edge of a ring 37 40 which is positioned about the fitting 36 below the end of the coupling member 35. Anti-friction bearing elements 38 are interposed between these two so as to provide for free rotation of the ring 37 with respect to the tubing 4.

The fitting 36 below the ring 37 is threaded with threads of a larger diameter than those at its upper end for the purpose of receiving a retaining ring 39 having a groove in its outer surface within which is disposed a packing 40. It 50 is noted that the upper end of this retaining ring 39 normally forms a stop to retain the ring 37 in its proper position with respect to the lower end of the coupling member 35. The lower end of the member 39 is provided with a downwardly 55 extending skirt portion 41 spaced from the fitting 36 and opposing the outwardly and upwardly extending flared portion 42 of this fitting. Between the skirt portion 41 and the flared portion 42 there are loosely retained the lugs 43 on the upper ends of the expanding dogs 44. The lower end of the fitting 36 is provided with a third exteriorly threaded portion to receive a nut 45 formed with an inclined upper end portion so that when it is screwed up on the fitting 36 it will 60 contact the lower ends of the expanding dogs 44 and force them radially outwardly. The nut 45 is prevented from being screwed off the lower end of the fitting 36 by means of a locking nut 46 held in place by locking pin or other desirable means. 70

Screwed into the upper end of the fitting 11 above the member 31 is the lower end of the screen pipe 47 through which the production of the well is adapted to enter after the well is completed. This screen, as hereinbefore stated, extends 75

through the producing formation and at its upper end may be provided with unperforated pipe and liner such as indicated by the numeral 48.

At the upper end of the pipe 48 there is secured to this pipe a special packer apparatus, a special fitting 48' being provided for attachment to the upper end of the pipe 48. The walls of the fitting 48' are off-set outwardly, and at the upper end thereof this fitting is connected to a second special fitting 49. Just above the upper end of the fitting 48' the fitting 49 is recessed interiorly to receive the slips 50 and above this position the member is recessed on its outer surface to receive the lower end of the packer. The upper end of the fitting 49 is tapered off as shown at 51, this portion lying within and being surrounded by one of the packing elements.

Slidably mounted within the fitting 49 and the upper end of the pipe 48 is a third special fitting 52. The slips 50 previously referred to are so arranged as to permit downward sliding movement of the fitting 52, but to prevent upward sliding movement thereof with respect to the fitting 49. When the device is being lowered into the well these two fittings 49 and 52 are secured in a predetermined position with respect to each other by means of shear pins 53. Adjacent its upper end, the fitting 52 is provided with an outwardly extending flange forming a downwardly facing shoulder which, when in the position illustrated in Fig. 4 before the shear pins 53 have been sheared off, is located a considerable distance above the upper end of the fitting 49. Between the shoulders provided by these two fittings there is wrapped a packer element 54 consisting usually of layers of canvas or similar material bound in place onto the respective elements at its opposite ends by means of bands 55. This packer is adapted to form the seal between the liner 48 and the interior of the lower end of the casing.

Seated upon the upper face of the outwardly extending flange of the fitting 52 is a third special fitting 56 secured to the fitting 52 by means of shear pins 57. Seated on the upper end of the fitting 52 and in a slightly recessed portion of the fitting 56 is a second packing element 58. Above this element and within the fitting 56 is the expanding member 59 about which are provided slips 60. These slips are so arranged as to permit downward movement of this expanding element 59 but to prevent upward movement thereof with respect to fitting 56. The upper end of the expanding member 59 is threaded into the lower end of the fitting 61, which in turn fits within the upper end of the fitting 56, and is secured therein by means of shear pins 62.

The fitting 61 is threadedly connected at its upper end to the end member 63 of the packer assembly, the fitting 61 and the member 63 being recessed on their inner surfaces to receive the slips 64. The slips 64 are seated in a downwardly tapered portion 65 of the recess in the member 61 and are downwardly pressed by means of a spring 66.

Interposed in that portion of the tubing 4 which passes through the packer assembly just described is a section of enlarged external diameter indicated by the numeral 67, and provided with a very smooth or polished exterior. Adjacent the lower end of this portion 67 is an outwardly extending ring 68 illustrated in detail in Fig. 10. This ring provides an upwardly facing shoulder and fits fairly snugly within the fitting 52. It is provided with notches or grooves about its exterior surface at intervals for the purpose of per-

mitting movement of fluid past the ring during the movement of the tubing with respect to the packer assembly.

In operation, the casing 1 is set in the ordinary manner and the hole is drilled into the producing formation. The tubing is then lowered into the well with the lower end thereof secured to the interior of the set shoe as illustrated in Fig. 3 of the drawings. The screen pipe 47 and the packer assembly above described are mounted on the set shoe in the manner illustrated. When the set shoe has reached the bottom of the well, the well may be washed by pumping fluid downwardly through the tubing and through the openings 24 and 25 in the valve within the set shoe, these openings being so positioned as to register with each other before the tubing is lowered into the well. The wash which is thus forced downwardly through the tubing will force the valve 14 open and pass out through the openings 7 in the bottom of the set shoe.

After the well has been sufficiently washed outside of the screen 47, the tubing will be rotated to the right to cause the nut 45, which is threaded onto the fitting 36 by a left hand thread, to move downwardly with respect to this fitting. It will be noted at this point that the ring 37 is seated upon the upper end of the sleeve-like portion 32 and will serve to support such portion of the weight of the tubing as is allowed to rest thereupon. Leakage between the lower end of the fitting 36 and the set shoe is prevented by means of the packing 40 which seals against the interior of the sleeve-like member 32. The nut 45 is prevented from rotation by means of lugs 45' formed on its exterior surface and engaging with the stop element 34. As the nut 45 is moved downwardly by rotation of the tubing to the right, it will be seen that it will move away from the lower ends of the suspended dogs 44, and will allow these dogs to fall inwardly and away from the shoulder 33. When the nut 45 has moved downwardly by a predetermined amount the lugs 45 will be disengaged from the stop members 34 but will have moved into engagement with the lugs 29 in the element 21 of the valve. Further rotation will cause the element 21 to rotate with respect to the element 19 of the valve and move the opening 25 out of register with the opening 24, thus closing the valve. When the element 21 has been moved sufficiently, the stop 26 thereon will contact with the stop lug 27 on the element 19, and the operator at the top of the well will be informed, both by the resistance to further rotation of the tubing and by the increased back pressure against the operation of the pumps and the consequent stopping or stalling thereof, that the valve is properly closed.

It will now be seen that the tubing may be lifted and that it will not be found to be connected with the set shoe and the screen because of the fact that the expanding dogs have moved inwardly and can pass upwardly through the sleeve-like portion 32. The tubing is then raised a distance equivalent to the amount which it is desired for it to hang above the lower end of the screen, plus the estimated amount which the packer elements 54 and 58 will be compressed in forming their respective seals. This distance can be very accurately determined from data available from previous experience. It will be noted that this upward movement of the tubing is permitted through the packer assembly

because the slips 64 are so positioned as to permit upward movement and prevent downward movement of the tubing through this assembly.

After the tubing has been raised the desired amount it is then again lowered. At this point, however, the slips 64 will grip the tubing, and further lowering of the tubing will cause the weight of the tubing to be placed upon the fitting 61 and the expanding element 59. The shear pins 62 will by the weight of the tubing be sheared off and the element 59 will be moved downwardly with respect to the fittings 56 and 52 so as to expand the packer element 58 and form a seal between the member 67 on the tubing and the fitting 56 which is connected to the well liner.

The weight of the tubing will also, as the packing 58 is expanded and becomes more solid, be transmitted to the fitting 52, thus causing the severance of the shear pins 53 and permitting the fitting 52 to move downwardly with respect to the fitting 49. It will readily be seen that this movement will cause the expansion of the packer element 54 so as to form a seal between the well liner and the interior of the lower end of the casing. It is to be noted that the expanding element 59 is prevented from upward sliding movement with respect to the fitting 56 by means of the slips 60 and that the packer element 58 will thus be held in expanded position. Likewise, the fitting 52 will be prevented from upward movement with respect to the fitting 49, and the packer element 54 will thus be held in expanded position. After the packer elements have thus been set or expanded to form the desired seals, the tubing may be hung and the well completed in any well known and desirable manner.

After a well has been producing for some time, or even in some instances before it has produced to any substantial extent, it is desired to withdraw the tubing from the well, and even to withdraw the screen and liner in order to carry out some operation which will improve the production of the well. With this invention, when such is desired the tubing is simply pulled upwardly, and since the member 67 is a smooth and polished member, the tubing may slide upwardly through the packing 58 which is shown in its expanded position in Fig. 2. However, when the ring 68 comes in contact with the lower end of the packing 58, it will stop further sliding movement of the tubing with respect to this packer element, and will cause the pull being exerted on the tubing to be exerted directly against the fitting 56 through the expander element 59 and the slips 60. This will cause the shearing of the shear pins 57, and the tubing may then be withdrawn from the well, together with the upper portion of the packing assembly. It will be noted that in carrying out this operation, no portion of the packing assembly has been damaged in any way, the severance being accomplished by the breaking of the shear pins provided for that purpose.

If now it be found desirable to also remove the screen, liner and set shoe, a cutting tool may be lowered past the packer element 54 and the liner severed therebelow. This packer element 54 may then be forced upwardly and out of the well. With the packer element 54 and its related elements out of the way, a tubing may again be lowered and caused to engage with the shoe at the lower end of the screen by reversing the

process above described. The screen and liner may then be easily removed from the well.

It will be understood that in some instances it may be possible to remove the packer element 54 by simply pulling upwardly on the set shoe 5 at the bottom of the screen and liner, thus removing the packer element, the screen and the liner in one continuous operation.

It will further be appreciated that there may be other variations in the method, as well as in the details of construction of the apparatus, and the combination of the various parts without departing from the spirit or scope of this invention.

From the foregoing, it will be seen that a means 15 has been provided for carrying out all the objects and advantages sought by this invention.

Having described my invention, I claim:

1. In a well packer combination, an outer packer adapted to be expanded outwardly against 20 the interior of a conduit, an inner packer initially out of contact with and adapted to be expanded inwardly against the exterior of a second conduit, and means for expanding both of said packers by manipulation of said last mentioned conduit. 25

2. In a well packer combination, an outer packer adapted to be expanded outwardly against the interior of a conduit, an inner packer adapted to be expanded inwardly against the exterior of a second conduit, means for locking said packers 30 in expanded position, and means on said last mentioned conduit for removing said inner packer in expanded condition.

3. In a well packer combination, an outer packer adapted to be expanded outwardly against 35 the interior of a conduit, and inner packer initially out of contact with and adapted to be expanded inwardly against the exterior of a second conduit, and means on said last mentioned conduit for removing said inner packer after the 40 same has been expanded.

4. In a well packer combination, an outwardly expansible packer, an inwardly expansible packer, means detachably securing said packers together, and means for removing one of said 45 packers from the well independently of the other.

5. In a well packer combination, an outwardly expansible packer, an inwardly expansible packer, frangible means securing said packers together, and means for fracturing said frangible means 50 and removing one of said packers from the other after the same have been expanded.

6. In a well packer combination, an outwardly expansible packer, an inwardly expansible packer, frangible means for holding said packers in unexpanded position, means for fracturing said 55 frangible means and expanding said packers, frangible means securing said packers together, and means for preventing the fracture of said last mentioned frangible means during the fracturing 60 of said first mentioned frangible means and the expansion of said packers.

7. In a well packer combination, an outwardly expansible packer, an inwardly expansible packer, frangible means for holding said packers in unexpanded position, means for fracturing said 65 frangible means and expanding said packers, frangible means securing said packers together, means for preventing the fracture of said last mentioned frangible means during the fracturing 70 of said first mentioned frangible means and the expansion of said packers, and means for fracturing said last mentioned frangible means and separating said packers after the same have been expanded. 75

8. In a well packer combination, an outwardly expansible packer, an inwardly expansible packer, said packers being in sealing engagement with each other and means joining said packers together for ready detachment from each other.
9. In a packer combination, an outwardly expansible packer, an inwardly expansible packer, and frangible means joining said packers together.
10. 10. In a packer combination, an outwardly expansible packer, an inwardly expansible packer, and an abutment means interposed between and common to said packers, whereby compressive force exerted upon one of said packers to expand

the same laterally will be transmitted through said abutment to the other packer to expand it also.

11. In a packer combination, an outwardly expansible packer, an inwardly expansible packer, and an abutment means interposed between and common to said packers, whereby compressive force exerted upon one of said packers to expand the same laterally will be transmitted through said abutment to the other packer to expand it 10 also, said abutment means comprising two relatively movable parts and a frangible connection securing said parts together.

CICERO C. BROWN.
